CLAIM

The ornamental design for a handle for a veterinary dental tool, as shown and described.

DESCRIPTION

FIG. 1 is a front, top, right perspective view for a handle for a veterinary dental tool, showing the new design;

FIG. 2 is a top plan view thereof;

FIG. 3 is a right side elevation view thereof;

FIG. 4 is a front elevation view thereof;

FIG. 5 is a rear elevation view thereof;

FIG. 6 is a bottom plan view thereof; and,

FIG. 7 is a left side elevation view thereof.

The broken lines of even length shown in the drawings illustrate portions of the handle for a veterinary dental tool that form no part of the claimed design.
